UNITED STATES PATENT OFFICE

2,431,263

RETAINING MEANS FOR TOILET SEAT COVERS

Eric H. Lundgren, Oakland, Calif.

Application January 18, 1945, Serial No. 573,349

7 Claims. (Cl. 4—236)

1

This invention relates to structurally novel and improved hinging and attaching means for a conventional toilet seat and an associated cover, for said seat, and the primary purpose of the invention is to provide simple and expedient safety means whereby it is possible to temporarily lock and retain the cover and seat assembly in a closed position, this under predetermined circumstances.

It is a matter of common knowledge that small children often throw toys and many and different types of articles and objects into toilet bowls. Thus, the water discharge line is clogged or completely stopped up. In an effort to prevent such nuisances, it is the purpose of the present invention to provide reliable and fool-proof means whereby the lid or cover can be fastened and "locked" whenever necessary or desired, in a closed position.

In carrying out the principles of the present invention, I have evolved and produced simple lug-equipped hinge brackets on the cover, the lugs being adapted to coact with projectible and retractible detents, said detents being carried by spring-projected, manually released latch devices, the latter slidably mounted in a special sheath-like tube which is employed to hingedly attach the seat and lid to the stock or standard bowl.

Other features and advantages will become more readily apparent from the following description and the accompanying illustrative drawings.

In the drawings, wherein like numerals are employed to designate like parts throughout the views:

Figure 1 is a fragmentary top plan view showing a portion of a bowl, a seat, a cover for the latter, and structural means which I have expressly devised to lock and unlock said cover.

Figure 2 is an enlarged fragmentary side elevational view of the bowl, seat and cover, with portions of the invention broken away and shown in section, the latter being about on the plane of the line 2—2 of Figure 1.

Figure 3 is a similar view, this to show the manner in which the locking and unlocking means functions.

Figure 4 is a perspective view of one of the manually controlled latches.

Figure 5 is a fragmentary perspective view of one end of the slotted tube, the latter rotated to a position to show the slot and keeper notches.

Referring now to the drawings by distinguishing reference numerals, it will be seen that the bowl or hopper is denoted by the numeral 6, the seat at 7 and the lid or cover at 8. The numerals

2

9 designate the adapter fixtures bolted to the extension shelf on the hopper, as shown in Figures 1 and 2. These are the customary fixtures, and in the present instance include ring-like bearings 10, said bearings serving to accommodate the projecting end portions of a horizontal tube 11. This tube serves as a housing for the enclosed mechanism and also as a fixed journal for the seat and cover hinges. The end portions of said tube 11 are fixed in the adapter eyes 12 by assembling and retaining pins 13, as shown in Figures 1 and 2.

Closing plugs 14 are fitted into the slotted ends 16 of the tube. The slots 16 are provided at spaced points (see Figures 1 and 5) with longitudinally spaced notches 17 and 18 which constitute selectively usable inner and outer keeper seats. A pair of latch devices of the type shown in Figure 4, are employed, these being denoted by the numerals 19, each latch device comprising a slidable pin or rod 20 having an L-shaped detent or retainer 21 at one end and a lateral finger grip, suitably knobbed, as at 22, this at the opposite end. These latches are slidably mounted in opposite end portions of the slotted tube 11 and are pressed away from one another by a central coiled spring 23 which is interposed therebetween, as shown in Figure 1.

The toilet seat 7 is provided with appropriately shaped attaching brackets 24 having caps 25 fitting over the ends of the tube 11 and constituting appropriate hinges for said seat. The seat, as usual, hinges independently of the cover 8. The cover is also provided with similar brackets 26 and these are formed with hinge rings 27 which embrace the tube 11. Thus, the tube serves as a pintle for the respective brackets 24 and 25. It will be noted that the hinge-rings 27 are provided with integral radial lugs 28 and these constitute stops. Then too, the aforementioned shiftable detents 21 are suitably arranged and are thus engageable with the stop lugs.

When the cover 8 is unlocked and free to swing, the latch devices 19 are in the retracted positions seen in Figure 1. Thus, the detents are then disengaged from the coacting rotatable lugs 28. When however, it is desired to "lock" the cover in closed position, the finger-grips 22 are grasped, lifted up and disengaged from the keeper notches 18, whereupon the spring means 23 comes into play and forces the respective rods 20 and their detents 21 underneath the lugs 28. The finger-grips 22 are then rocked down and seated in the keeper notches 17, whereby to "lock" the latches and to, in turn, lock the cover. The cover is thus closed and retained in closed position to prevent

it being opened by small children to the disadvantages heretofore mentioned. When a grown-up desires to use the toilet, all that is necessary is to release and then press the finger-grips 22 of the respective latch devices together against the tension of the spring 23 and to disengage the detents 21 from the lugs 28. The cover is then free to be handled and used in the customary manner. Needless to say, the shanks of the finger-grips 22 alternately coact with keeper notches 17 and 18 to maintain the latches "in" and "out" while the lugs 28 and detents 21 do the "locking."

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a structure of the class described, a toilet bowl, a pair of fixtures mounted thereon, a tubular rod mounted in said fixtures, a toilet seat, brackets carried by said seat, said brackets terminating in caps, said caps fitting hingedly over the adjacent outer ends of said tubular rod, a lid forming a cover for said seat, said lid being provided with brackets, said brackets terminating in hinge rings, and said hinge rings surrounding said tubular rod and being provided with outstanding stop lugs, and latch devices mounted in said rod and having detents releasably engageable with the lugs.

2. In a structure of the class described, in combination, a hopper, a pair of adapter fixtures thereon, a tubular rod mounted horizontally in said adapter fixtures, a seat hingedly connected with said rod, a cover for said seat having brackets formed with hinges hingedly connected with said rod, said hinges having outstanding lugs, and a pair of finger grip-equipped latch devices slidably mounted in said rod and provided with detents engageable with said lugs.

3. In a structure of the class described, in combination, a hopper, a pair of adapter fixtures thereon, a tubular rod mounted horizontally in said adapter fixtures, a seat hingedly connected with said rod, a cover for said seat having brackets formed with hinges hingedly connected with said rod, said hinges having outstanding lugs, and a pair of finger grip-equipped latch devices slidably mounted in said rod and provided with detents engageable with said lugs, together with spring means in said tubular rod interposed between the latch devices.

4. In a structural assemblage of the class described, a tubular journal-forming rod, and means for mounting same on a hopper, said rod being provided with longitudinal slots, said slots having keeper notches formed therein, a cover, brackets connected with said cover, said brackets having hinge rings surrounding the end portions of the rod, said hinge rings being provided with out-

standing stop lugs, a pair of latches slidably mounted in said rod, said latches having spring-pressed plunger pins, and said pins being provided with outstanding lateral elements, one of said elements constituting a detent engageable with the adjacent lug, and the other element a finger-grip.

5. In a structural assemblage of the class described, a toilet bowl, a pair of hinge rod supporting and accommodation fixtures rigidly mounted on said bowl, a rod fixedly mounted in said fixtures and disposed in parallelism above the adjacent surface of said bowl, a toilet seat for said bowl, brackets carried by and projecting from the rear end of said seat and hingedly connected with said rod, a lid forming a cover for said seat, brackets mounted on said lid, said brackets terminating in hinge rings surrounding said rod and provided with stop lugs, and latch devices slidably supported by said rod and having detents releasably engageable with said lugs.

6. In a structural assemblage of the class described, a toilet bowl, a pair of hinge rod supporting and accommodation fixtures rigidly mounted on said bowl, a rod fixedly mounted in said fixtures and disposed in parallelism above the adjacent surface of said bowl, a toilet seat for said bowl, brackets carried by and projecting from the rear end of said seat and hingedly connected with said rod, a lid forming a cover for said seat, brackets mounted on said lid, said brackets terminating in hinge rings surrounding said rod and provided with stop lugs, and manually controlled projectable and retractable latch means carried by said rod for temporarily holding the cover in closed position against the seat when said seat is against the bowl, said latch means being releasably engageable with said lugs.

7. In a structural assemblage of the class described, a toilet bowl, a pair of fixtures rigidly mounted on said bowl, a seat and lid supporting and attaching rod mounted horizontally and fixedly in said fixtures, a toilet seat co-acting with said bowl, brackets rigidly mounted on said seat, said brackets terminating in caps and said caps fitting hingedly over the outer ends of said rod, a lid forming a cover for said seat, additional brackets mounted on said lid, said brackets terminating in hinge rings, said hinge rings surrounding said rod, said hinge rings being provided with latch accommodating elements, and latches carried by said rod and releasably engageable with said elements.
